PASSENGER BUS

Charles W. Poole, Redlands, Calif., assignor to
Westinghouse Electric Corporation

Filed May 24, 1971, Ser. No. 146,612

Term of patent 14 years

Int. Cl. D12—08

U.S. Cl. D14—3

FIG.1.

FIG.5.

FIG. 2.

FIG. 3.

FIG. 4.

FIG. 1 is a perspective view of a passenger bus showing my new design;

FIG. 2 is a top plan view;

FIG. 3 is an elevational side view;

FIG. 4 is an elevational front view; and

FIG. 5 is an elevational rear view.

The side opposite to the side shown in FIG. 3 is substantially the same in appearance as the side shown in FIG. 3.

I claim:

The ornamental design for a passenger bus, substantially as shown and described.
